(57) **CLAIM**

The ornamental design for an insulated cinch pack, as shown.

DESCRIPTION

FIG. 1 is a perspective view of an insulated cinchpack; FIG. 2 is a front view of the insulated cinchpack; FIG. 3 is a rear view of the insulated cinchpack; FIG. 4 is a right side view of the insulated cinchpack; FIG. 5 is a left side view of the insulated cinchpack; FIG. 6 is a top view of the insulated cinchpack; and, FIG. 7 is a bottom view of the insulated cinchpack. The broken line elements in all views are for illustrative and environmental purposes only and form no part of the claimed design.
